Primary Examiner — Adir Aronovich(74) *Attorney, Agent, or Firm* — Michael Best & Friedrich
LLP(57) **CLAIM**

The ornamental design for a camera, as shown and described.

DESCRIPTION

FIG. 1 is a front, top, right perspective view of a camera showing my new design;

FIG. 2 is a rear, top, left perspective view thereof;

FIG. 3 is a front elevational view thereof;

FIG. 4 is a rear elevational view thereof;

FIG. 5 is a left side elevational view thereof; and,

FIG. 6 is a top plan view thereof.

The broken lines illustrate unclaimed portions of the camera and form no part of the claimed design.

1 Claim, 5 Drawing Sheets(56)
